UNITED STATES PATENT OFFICE

95,798

DESIGN FOR A VANITY CASE

Harry L. Berinstein, Elmira, N. Y.

Application April 2, 1935, Serial No. 56,183

Term of patent 3½ years

To all whom it may concern:

Be it known that I, Harry L. Berinstein, a citizen of the United States of America, residing at Elmira, in the county of Chemung and State of New York, have invented certain new, original, and ornamental Design for a Vanity Case, of which the following is a specification, reference being had to the accompanying drawing, forming part thereof.

Figure 1 is a front elevational view of a side of the vanity case, showing my new design;

Figure 2 is a side view of the same;

Figure 3 is a view of the end of the device showing the clasp; and

Figure 4 is an end view opposite from that shown in Figure 3.

I claim:—

The ornamental design for a vanity case, as shown.
